United States Patent Office

Des. 183,534
Patented Sept. 16, 1958

183,534

FISHING POLE HOLDER OR THE LIKE

Roy Menshouse, Covington, Ky.

Application February 21, 1957, Serial No. 44,949

Term of patent 14 years

(Cl. D31—4)

Fig. 1 is a side elevational view of a fishing pole holder or the like, showing my new design.

Fig. 2 is a side elevational view of the opposite side of Fig. 1.

Fig. 3 is a top perspective view of Fig. 1.

Fig. 4 is a front elevational view of Fig. 1.

I claim:

The ornamental design for a fishing pole holder or the like, as shown.
